PORTRABLE TRACER ATTACHMENT FOR LATHES

James B. Barsby, 2126 Berkeley Ave., Los Angeles, Calif.,
and Charles E. Whittington, 1709 Matchleaf Ave., La
Puente, Calif.

Filed June 17, 1964, Ser. No. 80,436

Term of patent 14 years

(Cl. D55—1)

FIG. 1

FIG. 2

FIG. 3

FIG. 4

FIG. 1 is a top plan view of a portable tracer attachment for lathes, showing my new designs;

FIG. 2 is a front elevation thereof;

FIG. 3 is a side view thereof with a partial cross-section taken at line 3—3 of FIG. 2; and

FIG. 4 is a fragmentary bottom plan view of the tracer head element taken at line 4—4 of FIG. 2.

We claim:

The ornamental design for a portable tracer attachment for lathes, as shown.
